1881.

UNITED STATES PATENT OFFICE.

JOHN W. LEFFERTS, OF BALTIMORE, MARYLAND, ASSIGNOR OF ONE-HALF
TO ROBERT B. PUMPHREY, OF SAME PLACE.

HORSE-DETACHER.

SPECIFICATION forming part of Letters Patent No. 245,730, dated August 16, 1881.

Application filed January 22, 1881. (Model.)

To all whom it may concern:

Be it known that I, JOHN W. LEFFERTS, of the city of Baltimore and State of Maryland, have invented certain Improvements in Carriages and other Vehicles, of which the following is a specification; and I do hereby declare that in the same is contained a full, clear, and exact description of my said invention, reference being had to the accompanying drawings, and to the letters of reference marked thereon.

The first part of my invention refers to improvements in the single-tree and the trace-detaching devices applied thereto, and the second part of the said invention has reference to improved means of attaching the breeching-straps to the shafts of the vehicle, the object of this part of the invention being to admit of the automatic detachment of the harness from the said vehicle after its disconnection from the single-tree aforesaid.

In the further description of my invention and the manner in which the same is operated, reference is made to the accompanying drawings, forming a part hereof, and in which—

Figure I is an exterior view of a carriage to which my invention is applied. Figs. II and III are views of the single-tree on an enlarged scale. Figs. IV and V are views of the improved device for attaching the breeching-straps to the shafts of the vehicle.

Similar letters of reference indicate similar parts in all the views.

A is the single-tree, which, in the main, is of the ordinary description, and connected to the carriage in the usual manner.

B B are hooked levers pivoted to the ends of the single-tree, the hooked ends of which are adapted for attachment to the traces. The straight arms of the said levers are held in a position nearly in contact with the single-tree by means of hooks C, permanently fastened thereto. A rod, D, the ends of which rest in suitable bearings in the hooks C, is provided with cams E, which, as the said rod is partially revolved, are brought into contact with the straight arms of the levers and force them out of the said hooks. When the long arms of the lever B are released from the

hooks, as described, the strain on the traces causes the said levers to assume the position shown in dotted lines, which effects the release of the traces. The means for communicating motion to the rod D consists of a lever, F, the free end of which is adapted for connection with a strap extending to the interior of the vehicle.

In order to prevent the accidental release of the levers B when there is no strain on the traces, I provide the single-tree with the springs a or equivalent devices.

The breeching-straps, which in ordinary cases are fastened directly to the shafts of the vehicle, are in the present invention attached to removable blocks b, resting in suitable carriers, c, secured to the under part of the shafts. In backing the vehicle, the blocks b are brought into contact with the ends of the carriers, but in the forward movement of the horse, after its release from the single-tree, the blocks are withdrawn from the carriers and all connection between the horse and the vehicle severed.

When my invention is applied to a vehicle having a pole instead of shafts, the removable block and the carrier are applied to the pole and connect with the breast-strap of the harness.

Having thus described my invention, what I claim as new, and wish to secure by Letters Patent of the United States, is—

1. In combination with the single tree A, the hooked pivoted levers B, hooks C, rod D, and cams E, the said rod being provided with means for turning it to effect the disconnection of the traces, substantially as herein specified.

2. As means for connecting the breeching-straps to the shafts of a carriage or other vehicle, the carrier c, combined with the removable block b, substantially as herein set forth.

In testimony whereof I have hereunto subscribed my name this 18th day of March, A.D. 1879.

JOHN W. LEFFERTS.
